[57] CLAIM

The ornamental design for a hand-held infrared remote control unit for a digital image viewer system, as shown and described.

DESCRIPTION

FIG. 1 is a top plan view of a hand-held infrared remote control unit for a digital image viewer system showing our new design;

FIG. 2 is a right side elevational view thereof, the left side elevation being a mirror image thereof;

FIG. 3 is a bottom plan view thereof;

FIG. 4 is a front elevation view thereof;

FIG. 5 is a rear elevational view thereof;

FIG. 6 is a perspective view showing the bottom, left side and front end thereof; and,

FIG. 7 is a perspective view showing the top and right side thereof.
